UNITED STATES PATENT OFFICE.

CHARLES ALVIN DREISBACH, OF NEW HAVEN, CONNECTICUT.

PULVERIZER.

1,238,115.

Specification of Letters Patent. Patented Aug. 28, 1917.

Application filed November 26, 1915. Serial No. 63,372.

To all whom it may concern:

Be it known that I, CHARLES A. DREISBACH, a citizen of the United States, residing at New Haven, in the county of New Haven and State of Connecticut, have invented certain new and useful Improvements in Pulverizers, of which the following is a specification, reference being had therein to the accompanying drawings.

10 My invention relates to a new and improved pulverizer of the type designed to crush slag cinders so as to separate the metal therefrom.

It is the object of my invention, among 15 other things, to produce an apparatus of this character wherein the water within the barrel may be discharged from the side thereof rather than through perforations in its periphery, as has heretofore been the 20 practice; to mount the upper of the crushing rolls so that it may have great ease of movement and flexibility; and in other ways to materially improve the pulverizing devices heretofore made.

25 To these, and other ends, my invention consists in the pulverizer having certain details of construction and combinations of parts, as will be hereinafter described and more particularly pointed out in the claims.

30 Referring to the drawings, in which like numerals of reference designate like parts in the several figures;

Figure 1 is a front elevation, partly in section, of an apparatus embodying one 35 form in which my invention may be constructed;

Fig. 2 is an end view thereof, taken upon line *a*—*b* of Fig. 1;

Fig. 3 is a sectional elevation thereof, 40 taken upon line *c*—*d* of Fig. 1;

Fig. 4 is a fragmentary end elevation looking toward the right of Fig. 1;

Fig. 5 is a sectional view of the drum, taken upon line *e*—*f* of Fig. 3; and

45 Fig. 6 is a fragmentary view of the settling tank and the over-flow trough connected therewith.

Heretofore the barrel or drum has been 50 provided with a plurality of openings in its outer shell through which the water enters the barrel, but in some classes of work this is objectionable, because the holes become clogged and the water does not enter the barrel in sufficient quantities to do effective work, and again, the upper of the 55 crushing rolls has been so mounted that it

moves in substantially a straight line and thereafter does not bear with equal pressure upon the lower crushing roll at all times. I have obviated both of these disadvantages 60 in this invention by providing means for supplying the barrel with water without admitting it through apertures in the outer shell thereof, and also by making the upper of the crushing rolls more flexible in its action, and so mounted that it always bears 65 with equal pressure upon the lower crushing roll.

In the practice of my invention I provide a pair of substantially parallel uprights 1—1, to which is attached a circular head plate 2, which forms a stationary end for the barrel. The barrel 3 has upon opposite ends thereof the external annular flanges 4 and 5, which are in frictional contact with the rollers 6 that are journaled in the adjustable bearings 7. A shaft 8 is rotatably mounted in the head plates 2, and fixed thereon is a crushing roll 9. Upon the outer end of this shaft is a gear wheel 10, the teeth of which mesh into those of the pinion 11 fixed on the shaft 12. Fast and loose pulleys 13 are fixed on this latter shaft and thereby provide convenient means for rotating all of said shafts and the crushing roll 9 through the middle of a plate, as is common in the art. An auxiliary shaft 15 is rotatably mounted in a bracket 14 attached to one of the frames 1 and fixed thereon is a sprocket wheel 16, which is 70 operatively connected with a sprocket pinion 17 upon the shaft 8 by the chain 18. Also fixed upon the shaft 15 is a pinion 19, shown by dotted lines in Fig. 2, both of which mesh into those of the internal gear 20 on 75 the flange 5.

By the means above described the barrel 3 is rotated and the crushing roll 9 at one and the same time, and through the action of the shaft 8.

100 A second crushing roll 21 is fixed upon the shaft 22 journaled in the yoke 23 that is movably mounted upon the shaft 24 journaled at its opposite ends in the brackets 25. These brackets are fixed upon the inner faces 105 of the plates 2. This second crushing roll 21 bears by gravity against the roll 9 and through its pivot mounting is moved toward and away from the roll 9, its relative position depending upon the quantity of mate- 110 rial passing therebetween.

In one of the plates 2 is an opening 26,

through which the slag cinder is fed into the barrel and for convenience in delivering the cinders into the barrel, I have provided a feed chute 27 that is pivoted to one of the 5 head plates 2 at 28 and is secured in this position by a latch 29 on the spindle 30, which engages a lug 31 upon the chute.

The cinder as it falls into the barrel is deflected by the guard 47 and accumulates 10 upon the bottom of the barrel. It is then carried upwardly by the pallets 32, which discharge the cinder by gravity upon an apron 33, which is mounted upon said spindle 30 and guides the cinder between the 15 crushing rolls 9 and 21. After passing between the rolls the crushed cinder drops onto the bottom of the barrel and is again carried up by the pallets and recrushed, which operations are repeated until the 20 contents of the barrel are discharged by means hereafter described.

A water trough 34 is arranged so that the drum rotates therein and adjacent thereto is a settling tank 35 connected with the 25 trough 34 by a spillway 36, over which the water flows from said settling tank into said trough. Within the barrel, between the outer walls thereof and the inner walls 38 are a plurality of inner chambers 37, which 30 are radially separated from each other by partitions 39. During the rotation of said barrel water is admitted into the chambers 37 from the trough 34, through the openings 40 in the outside of the barrel and is 35 discharged into the barrel through the openings 41 upon the inside of the barrel. When the water in the barrel arrives at the level of the openings 48 in the plate 2, see Fig. 3, it overflows onto the spout 43 and is discharged 40 into the settling tank 35, from which it flows back into the water trough over the spillway 36. By this method of water distribution the water in the barrel is maintained at a level higher than that in the trough, is being 45 continually used and no new supply is required, thereby providing means for operating the device at the minimum expenditure for water supply. After passing between the rolls the light particles of the 50 cinder mass by the action of the water in the barrel and by its agitation are carried into the settling tank through the opening 48, and the heavy particles, which contain the metal, sink to the bottom of the barrel and 55 are again carried up and passed between the rolls, being continually subjected to successive crushing operations.

As the cinders are always wet when presented to the crushing rolls, there is no dust 60 in the operation of my device. It may be used, however, for dry grinding if desired, and for such use I may provide a hole 46 in one of the heads 2 to receive a dust flue leading to a suitable exhaust device (not 65 shown) by means of which the dust is drawn

off. After the cinder has been sufficiently ground the barrel is emptied by swinging the apron 33 through the manipulation of the handle 44 to the position shown by dotted lines in Fig. 3. In such position the material is deflected onto the stationary chute 45 in the barrel and over which the apron 33 normally lies. As the bottom of this chute is inclined downwardly the material slides onto the swinging chute 27, which is 75 in the position shown by dotted lines in Fig. 1, and thus forms a continuation of the chute 45.

Within reasonable limitations various modifications of my invention, aside from those herein suggested, may be adopted, and will readily suggest themselves to any person skilled in the art. I would therefore have it understood, that I do not limit myself to the exact construction herein shown 85 and described, but claim all that falls fairly within the spirit and scope of my invention.

What I claim as new and desire to secure by Letters Patent, is:—

1. In a crushing apparatus, the combination with a barrel; of a water trough, means for rotating said barrel so that a portion thereof passes through the water in said water trough, and means connected with said barrel for taking water from said trough and discharging it into said barrel in such manner that the level of the water within the barrel may be higher than within the trough.

2. In a crushing apparatus, the combination with a barrel having a plurality of chambers therein adjacent to its periphery with openings or ports connected therewith at different radial points about said barrel; of a water trough, means for rotating said barrel so that the portion of said barrel having the chambers therein passes through the water in said trough whereby water will enter said chambers from said trough and will be delivered into said barrel.

3. In a crushing apparatus, the combination with a barrel having a plurality of chambers therein adjacent to its periphery, each of said chambers having openings adjacent to the opposite ends thereof, the opening in one end being through the outside of said barrel and at the opposite end through the inside of said barrel; of a water trough, and means for rotating said barrel within said trough, so that the openings into said 115 chambers through the outside thereof pass through the water in said trough.

4. In a crushing apparatus, the combination with a barrel; of a water trough, means for rotating said barrel in said trough so 125 that water may be taken up from said trough and conveyed to the inside of said barrel and discharged therefrom at a level higher than the water in said trough.

5. In a crushing apparatus, the combina- 130

tion with a water trough; of a settling tank adjacent thereto and having connection therewith, whereby water in said settling tank will flow into said water trough, a barrel, means for rotating said barrel so that the periphery thereof passes through the water in said water trough, a discharge opening through one side of said barrel between the periphery and the axis thereof, 5 said discharge opening being at a point in a plane higher than the water in said trough, 10 and means connected with said barrel for taking water from said trough, discharging it into said barrel, and discharging it from said barrel through said discharge opening. 15

In testimony whereof I have hereunto affixed my signature.

CHARLES ALVIN DREISBACH.
